Design No. 19,867, dated June 3, 1890.

UNITED STATES PATENT OFFICE.

CHARLES THOMAS LA TOUR, OF PHILADELPHIA, PENNSYLVANIA, ASSIGNOR
TO CONYERS BUTTON AND MARTIN L. FINCKEL, BOTH OF SAME PLACE.

DESIGN FOR AN ORNAMENT FOR HOODS, &c.

SPECIFICATION forming part of Design No. 19,867, dated June 3, 1890.

Application filed January 23, 1890. Serial No. 337,911. Term of patent 7 years.

To all whom it may concern:

Be it known that I, CHARLES THOMAS LA TOUR, a citizen of the United States, and a resident of Philadelphia, Pennsylvania, have 5 invented a new and original Design for a Hood Ornament, of which the following is a specification.

My design for an ornament for knitted hoods or other apparel is clearly shown in the accompanying photographic representation, the essential feature of the design being a rounded fluffy band tapering from a point at or near the center toward each end, the end portions of the band showing rows of loops disposed 15 in spiral courses.

I claim—

The design for an ornament for hoods and other apparel of the rounded fluffy band tapering from the middle toward each end, the end portions of the band showing rows of loops 20 disposed in spiral courses.

In testimony whereof I have signed my name to this specification in the presence of two subscribing witnesses.

CHARLES THOS. LA TOUR.
